UNITED STATES PATENT OFFICE

GEORGE K. LORENZ, OF CLIFTON, NEW JERSEY

COMB-RETAINING DEVICE

Application filed September 25, 1929. Serial No. 394,986.

This invention relates to a device for retaining combs in hair, the combs being placed in position to curl the hair and left there for some time. The device is arranged 5 to engage the backs of combs which have their teeth directed toward each other.

The invention is illustrated in the accompanying drawing in which Figure 1 is a top view of my improved comb retainer. 10 Figure 2 is a side view of the device. Figure 3 is a view showing how the device is used, with the outline of a head and the combs shown in dotted outline.

The article has strands or strips of material, preferably elastic material. The device I illustrate is provided with two strands 10. Two are preferred as they keep the ends under equal strain and prevent tilting of the tabs. The tabs 11 are arranged at both ends 20 of the strand or strands. They are freely secured, that is, they can be turned under easily. The usual way to fasten them is to pass the strands through holes in the tabs and knot them as at 12.

25 The tabs are substantially triangular and are tapered toward the outside ends as at 13 and are usually rounded at the ends as at 14.

The tabs are flexible in the preferred form of article. I usually employ celluloid or the 30 like and this flexibility is desirable as it enables the tabs to be easily slid in under a comb.

In Figure 3 I show how the device is used. The outer combs 15 are placed in the hair 35 as are any other combs desired between them. The two tabs 11 are grasped, the elastic 10 is stretched, the tabs 11 are turned under and then slid underneath the combs 15. The 40 flexibility of the tabs takes up any lateral strain and the tabs do not injure the scalp or cause any discomfort.

I claim:

1. A comb retaining device comprising an 45 elastic strand and flat tabs secured to the ends of the strand said tabs each being substantially triangular in shape and secured at a broad end to the strand to present a narrow end for insertion into the hair under 50 a comb.

2. A comb retaining device comprising flat tabs of a generally triangular shape and a pair of parallel elastic strands each having its ends secured at the angle of a tab to present a narrow end for insertion under 55 a comb and to pull on the tabs without tilting them.

3. A comb retaining device comprising two tabs of flat material of generally triangular form with holes in two corners of 60 each and having the angle at the other corner rounded and elastic strands secured in the holes and connecting the tabs.

In testimony whereof I affix my signature.
